UNITED STATES PATENT OFFICE.

THOMAS JOHN WOODWARD, OF WEST BROMWICH, ENGLAND, ASSIGNOR
TO CHANCE BROTHERS AND CO. LIMITED, OF WEST SMETHWICK, NEAR
BIRMINGHAM, ENGLAND.

DESIGN FOR PLATE-GLASS.

SPECIFICATION forming part of Design No. 37,346, dated February 14, 1905.

Application filed January 5, 1905. Serial No. 239,815. Term of patent 14 years.

To all whom it may concern:

Be it known that I, THOMAS JOHN WOODWARD, a subject of the King of Great Britain, residing at No. 113 Beeches road, West Bromwich, England, have invented a new, original, and ornamental Design for Plate-Glass, of which the following is a specification, reference being had to the accompanying drawing, forming part hereof.

10 The drawing represents a face view of a

piece of plate-glass ornamented with my design.

What I claim as new, and desire to secure by Letters Patent, is—

15 The ornamental design for plate-glass, as shown.

THOMAS JOHN WOODWARD.
